US00D959975S

(12) **United States Design Patent** (10) **Patent No.:** **US D959,975 S**
Bercaw et al. (45) **Date of Patent:** **** Aug. 9, 2022**

(54) **BATH PRODUCT PACKAGING**

- (71) Applicant: **DA BOMB, LLC**, Edina, MN (US)
(72) Inventors: **Isabel R Bercaw**, Edina, MN (US);
Caroline F Bercaw, Edina, MN (US);
Benjamin T Bercaw, Edina, MN (US);
Kimberly D Bercaw, Edina, MN (US)
(73) Assignee: **Da BOMB, LLC**, Edina, MN (US)
(***) Term: **15 Years**
(21) Appl. No.: **29/658,607**
(22) Filed: **Aug. 1, 2018**

Related U.S. Application Data

- (63) Continuation of application No. 29/570,360, filed on Aug. 10, 2016, now Pat. No. Des. 827,425.

CLAIM

The ornamental design for bath product packaging, as shown and described.

DESCRIPTION

FIG. 1 is a top plan view of the bath product packaging showing our new design.

FIG. 2 is a right perspective view of the bath product packaging.

FIG. 3 is a bottom plan view of the bath product packaging.

FIG. 4 is a front perspective view of the bath product packaging.

FIG. 5 is a left perspective view of the bath product packaging.

FIG. 6 is a rear perspective view of the bath product packaging; and,

FIG. 7 is a perspective view showing the bath product packaging in an exploded position and in smaller scale than FIGS. 1-6.

The broken lines of FIGS. 1-7 illustrate portions of the bath product packaging that form no part of the claimed design.

1 Claim, 7 Drawing Sheets
